UNITED STATES PATENT OFFICE.

JAMES L. ROWLAND, OF NEW YORK, N. Y.

IMPROVEMENT IN THE MANUFACTURE OF ARTIFICIAL STONE.

Specification forming part of Letters Patent No. 149,682, dated April 14, 1874; application filed February 26, 1874.

To all whom it may concern:

Be it known that I, JAMES L. ROWLAND, formerly of Milwaukee and State of Wisconsin, but now of the city, county, and State of New York, have invented a new and improved mode of treating cement, combined or not with other material or substances, in the manufacture of artificial stone; and I do hereby declare that the following is a full, clear, and exact description thereof, reference being had to the accompanying drawing and the letters of reference thereon, constituting a part of this specification.

In the drawing, Figure 1 is a vertical longitudinal section of the apparatus which is intended to illustrate the principle of operating the indurating-chamber with carbonic-acid gas in the process of manufacturing artificial stone by the action of an acid on an alkaline base in solution, or in combination with water, in lieu of the mode of generating such gas by the burning of charcoal or other substances from which carbonic-acid gas may be set free by the action of fire. Fig. 2 is a top view of the indurating-chamber with the cover removed.

A is an indurating-chamber, in which blocks or articles made of cement, or cement properly combined with other suitable material or substances, as delivered from the molds, are placed, such blocks or articles being arranged therein in any suitable manner preparatory to their treatment, whereby they are indurated, and converted into artificial stone. In dotted lines a door, *b*, is shown, opening into said chamber; and *b'* indicates a covered opening in the top of the chamber, which opening is made available, when desired, to allow vapor or air to escape from the chamber. *A*¹ is a water-carbonator, or a carbonated-water charger, and consists of a strong water and gas tight vessel, of about eight or ten or more gallons capacity, made preferably of copper, and is provided at its lower end with a small pipe, *c*, to which a hose-pipe, *d*, may be attached, the pipe *c* being provided with a stop-cock, *e*. This charger *A*¹ terminates at its upper end in a screw-thread neck, *e*, through which is fitted a stop-cock, *f*. *A*² is a smaller cylinder or vessel, made of copper, and of a capacity to hold eight or ten or more ounces of sulphuric acid, and has an elongated neck, *e'*, constructed either so as to screw

tightly around or into the neck *e* of the charger *A*¹, the neck *e'* also being provided with a stop-cock, as at *f'*.

This charger or water-carbonator *A*¹ is charged by supplying it with such proper quantities of sulphuric acid and soda dissolved in water as will evolve gas enough to give a pressure sufficient to force the solution or charge from the charger *A*¹ through the pipe *d*, when properly arranged therefor, into the boxes *B*, *B*¹, and *B*², large quantities of the sulphuric acid and soda dissolved in water being used when it is desired to speedily supply the chamber *A* with gas, and in large quantities.

A medium charge for a charger of the dimensions given above is one or one and a half pound of bicarbonate of soda, about seven and a half gallons of water, and six or seven ounces of sulphuric acid. This charge is supplied to the charger *A*¹ as follows: Remove the cylinder *A*², then put in the water, and afterward the soda. This being done, pour the sulphuric acid into the cylinder *A*², and confine it therein by the stop-cock *f'*, after which screw the cylinder *A*² onto the charger *A*¹, as indicated in Fig. 1, after which, the cocks *f* and *f'* being opened, the acid will descend in regulated quantities, as desired, into the charger *A*¹, and therein mix with and act upon the soda in solution, which solution may now, under the pressure of the gas evolved, be allowed to escape through the pipe *d* by the stop-cock *c*, as desired, into the boxes *B*, *B*¹, and *B*², the supply to box *B*¹ being effected by the attachment of the tube *d* to the inlet-pipe *h*² of box *B*¹, or the insertion of the nozzle *d'* of the pipe *d* into the funnel *h* of pipe *h*¹, which discharges into the box *B*².

The boxes *B* and *B*², which are located the one within and the other without the indurating-chamber *A*, as shown, are charged in two ways: First, by supplying them, through the covers *g* and *g'*, with proper quantities of sulphuric acid and soda dissolved in water, or with powdered marble and sulphuric or muriatic acid diluted with water; and, secondly, by charging them the same as the box *B*¹ is charged, as above described.

It will thus be seen that the indurating-chamber *A* may be operated by the carbonic-acid

gas, whether generated directly in the boxes B or B², or generated in the charger A¹, and then ejected into the boxes B, B¹, or B². If the gas is generated in the boxes B or B² it escapes into the chamber A through the upper uncovered side of the box B² and the opening K of the box B, and in like manner escapes through the uncovered side of the box B¹ into the chamber A when injected into said boxes from the charger A¹ through the pipes h¹ h² leading thereto. Thus the indurating-chamber A may be charged by gas generated in either or both of the boxes B and B²; or it may be charged by gas generated in the charger A¹, which is passed therefrom into either the box B, from whence it escapes into the chamber A through an opening, k, or into the box B¹ or B², whence it escapes into the indurating-chamber A through the upper uncovered sides of boxes B¹ B²; or, the indurating-chamber A may be charged by gas generated in either one or both the boxes B B² at the same time it is receiving a charge from the carbonated water-charger A¹ into the box B¹.

It will be understood that when the acid, soda, and water are introduced into the charger A¹, they therein commingle and form a solution which is highly impregnated with carbonic-acid gas. This solution, while still in the charger, gives off a sufficient quantity of such gas to form in the upper portion of the charger a heavy pressure upon the solution; and thus, when the cocks c and c² are opened, the solution thus impregnated is forced into the box B, from whence the gas escapes into the chamber A through opening k. From the box, this solution having exhausted its gas, may be drawn off through the cock c³ preparatory to another such charge.

In like manner charges of solution which form carbonic-acid gas made in boxes B and B² may be withdrawn, whether formed therein in the first instance, or injected therein from the carbonated-water charger A¹.

By this mode of operating the indurating-chamber A, it will be observed that the solution is introduced into the chamber while impregnated with carbonic-acid gas. In other words, carbonated water is introduced into the indurating-chamber A, thus supplying the chamber with a moist gas, or gas and moisture commingled, which are absorbed in the cement or other articles placed in the indurating-chamber A, the moisture, while being absorbed by the cement, acting as a vehicle to carry the gas with it into the cement, and while absorbed effecting a chemical union of the gas and cement.

This process of operating or charging the chamber A or supplying it with carbonic acid, or this gas and vapor or moisture, is continued from one to two or three days, or longer, if necessary, the repetition of the charges, and the continuation of the process, depending upon the degree of induration desired to be given to the blocks or articles placed for treatment in the chamber A.

From the foregoing description of my mode of simultaneously applying moisture and gas, chemically generated, and in a cool state, to blocks and articles made of cement, or cement properly combined with other suitable material or substances for the purpose of indurating the same, it will be seen that I make provision for generating such gas either within or outside of the indurating-chamber—also for generating it simultaneously, if desirable, both within and outside of said chamber—whereby both modes may be made available for supplying an additional powerful volume of moistened gas to the cement or material desired to be indurated, when it is desired to hasten the process of indurating; and further, that such moisture and gas may at option be applied at varying points of locality within the chamber A, alternately or simultaneously, in order to supply the gas to the cement or material to be indurated in the most available and efficient manner.

In the construction of the indurating-chamber A, as stated in the specification of my Letters Patent No. 109,669, dated November 29, 1870, no peculiar form or mode or kind of material is requisite, further than that the chamber be made gas and vapor holding, and convenient for receiving the blocks or other articles for treatment; and if the chamber is intended to be removable, so constructed as to be easily put up or placed over, or over and around the block or other articles, and easily taken down and apart or removed.

When it is desired to operate the indurating-chamber A with a more copious supply of moisture than is furnished by the above-described modes of charging this chamber with carbonic-acid gas and moisture in the treatment of material or articles placed therein to be indurated, I introduce through suitable openings, as indicated at 1, 2, and 4, made at varying points in the chamber, carbonated water, or the charge from the carbonated-water charger A¹, in the form of finely-divided particles, as fine spray or mist, directly into the chamber, instead of the boxes B B¹ B², and directly to the material or articles placed therein for treatment or otherwise, as desired. In this case a nozzle, closed at its end and suitably pierced with many fine holes, or a nozzle terminating in the shape of, or having fitted to the end of it, a rose pierced with fine holes, as shown in the drawing, is used in connection with the pipe d, in order that the carbonated water on being forced through these holes may take the form of fine spray, mist, or vapor. When the openings 1, 2, and 4 are not used, they are closed gas-tight in any suitable manner. By this mode of charging or operating the chamber A with carbonated water—i. e., carbonic acid and moisture—the charged water, whether applied directly or not to the material or articles placed therein for treatment, is diffused as vapor into all portions of the chamber A, and the material or articles placed therein to be indurated or con-

verted into stone thus completely enveloped in an atmosphere of moist carbonic-acid gas, or the gas and moisture.

This latter mode of charging or operating the chamber A is used either in conjunction or not with the modes of charging this chamber first herein described; and they may be used either alternately or simultaneously with them, as may be deemed desirable, for the speedy and efficient induration of the material or articles desired to be converted into stone.

By the term "cement," as used in the foregoing portions of this specification, I mean to imply material or substances, such as quick-lime, hydraulic lime, magnesia, or their hydrates, the hydraulic cements, and others, combined or not two or more with one another, with which carbonic acid and water or moisture may be made to chemically unite and form a salt as a carbonate, and whether these salts or solids be formed by a direct chemical combination of the carbonic acid and water or moisture with such material or substances, or whether by a decomposition and a recombination.

The box B² is supplied with a cock, C⁴, for drawing off a spent charge, the same as in box B, and a similar cock and for the same purpose will, in practice, be applied to box B¹.

Having described my invention, what I claim as new, and desire to secure by Letters Patent, is—

1. The process of manufacturing artificial stone, whereby the hardening of blocks or other articles made of cement, or cement combined with other material or substances, is effected within the indurating-chamber by means of moisture and carbonic-acid gas generated either within said chamber, or by means of moisture and said gas generated within said chamber in combination with moisture and said gas generated outside of said chamber, substantially as described.

2. The process of manufacturing artificial stone, whereby the hardening of blocks or other articles made of cement, or cement combined with other material or substances, is effected within the indurating-chamber by means of moisture and carbonic-acid gas generated at varying points of locality within said chamber, substantially as described.

JAMES L. ROWLAND.
